UNITED STATES PATENT OFFICE

168,073

STOCKING

Charles A. Scott, Philadelphia, Pa., assignor to Carla Hosiery Co., Philadelphia, Pa., a corporation of Pennsylvania

Application December 5, 1951, Serial No. 17,610

Term of patent 14 years

(Cl. D47—7)

To all whom it may concern:

Be it known that I, Charles A. Scott, a citizen of the United States, residing at Philadelphia, Pennsylvania, have invented a new, original, and ornamental Design for a Stocking, of which the following is a specification, reference being had to the accompanying drawing, forming a part hereof.

Fig. 1 is a side elevational view of a stocking, showing my new design.

Fig. 2 is a fragmentary rear elevational view showing the stocking as it appears when worn.

Fig. 3 is an enlarged fragmentary front view illustrating the narrow plain knitted stripes in the lacy texture.

The instant stocking comprises a lace knit boot portion having narrow plain knitted vertical bands extending from the toe pocket to the shadow welt on the front and to the calf on the back, all as shown.

I claim:

The ornamental design for a stocking, as shown and described.

CHARLES A. SCOTT.
